US0D1091387S

(12) **United States Design Patent** (10) **Patent No.:** **US D1,091,387 S**
(45) **Date of Patent:** **** Sep. 2, 2025**

(54) **BIKE**

(71) Applicant: **RAZOR USA LLC**, Cerritos, CA (US)

(72) Inventor: **Ian Desberg**, Cerritos, CA (US)

(73) Assignee: **Razor USA LLC**, Cerritos, CA (US)

(**) Term: **15 Years**

(21) Appl. No.: **29/910,005**

(22) Filed: **Aug. 14, 2023**

(51) **LOC (15) Cl.** **12-11**

(52) **U.S. Cl.**

USPC **D12/111**

(58) **Field of Classification Search**
